CARRIER RACK OR HOLDER

William O. Humphries, Memphis, Tenn., assignor of one-half to Bry-Block Mercantile Corporation, Memphis, Tenn., a corporation of Tennessee

Application January 19, 1939, Serial No. 251,815

4 Claims. (Cl. 211—49)

The present invention relates to carrier racks and holders, and particularly to racks or holders for cash carriers commonly used in pneumatic conveying systems, and the invention aims generally to improve existing racks and holders of that type.

The arrangement of modern department stores usually provides for the placing of wrapping stations at selected places about the store where the sales clerks in nearby sections may make financial transactions with a central cashier's office, as well as have purchased articles wrapped. For this purpose there is usually associated with the wrapping station, one terminal of a pneumatic conveyor system, and of course a supply of carriers for such conveyor system must be maintained at each station.

Transactions in modern department stores may include different types of sales, such as cash sales, charge-take sales, charge-send, C. O. D. sales, and lay-away sales, and to facilitate the handling of these sales, it is desirable that the attendant at the wrapping station identify each respective kind of sale so that they may be expeditiously handled at the central cashier's office. This is advantageously accomplished by placing some distinguishing or identifying indicia on the carrier to indicate, at a glance, the type of the sale.

The above often results in considerable untidiness at the wrapping station and frequently there is considerable loss of time caused by the wrappers hunting for the proper carrier to designate the particular sale.

My invention aims to overcome the above stated objections by providing a carrier rack or holder for wrapping stations or conveyor terminals which will provide a means for readily segregating the carriers for different types of sales, expedite the handling of sales, and eliminate the untidy appearance of carriers lying around the station.

A further object of the invention is in the provision of a rack for carriers, which will prevent the possibility of a clerk filing the carrier away until after it has been opened and emptied.

With the above and other objects in view, I have selected for illustration one embodiment of the invention, more fully described in the following description and illustrated in the accompanying drawing, in which

Fig. 1 is a rear view of the carrier rack or holder;

Fig. 2 is a front view thereof;

Fig. 3 is a transverse sectional view on the line 3—3 of Fig. 2;

Fig. 4 is a vertical sectional view on the line 4—4 of Fig. 2; and

Fig. 5 is a perspective view of one conventional type of carrier.

In the illustrated embodiment of the invention there is provided a rack or holder 10 having a panel of sufficient length to constitute a part of a plurality of upright containers or trays 11, 10 for selectively holding and housing a plurality of cylindrical carriers 12, properly segregated into groups respecting different classes of sale. In the illustrated example, I have shown a rack composed of four containers or trays 11 for 16 housing carriers identified for "C. O. D. lay-away" sales; "Charge-send" sales; "Charge-take" sales; and "Cash" sales, respectively, though it will be understood that the numbers of trays 11 may be increased or decreased as 20 may be desired to meet the requirements of a particular store.

The trays 11 may be formed conveniently of a back panel member 13 which may extend the entire length of the rack, divided into sections 25 by a plurality of partition members 14 on one face thereof, each of which is preferably formed with guide members 15, extending longitudinally of the rack a definite distance on each side of the partitions 14, and in spaced relation to the 30 back member 13. The rack is preferably provided with a bottom member 16 extending the length thereof, and is formed with hand openings centrally of each tray to facilitate access to the carriers. The guide members 15 terminate short of the bottom 16, a distance equal, at least, to the maximum diameter of the carrier 12, to provide discharge openings thereof, thus facilitating removal of the carrier 12 from the bottom of the trays 11.

The carriers 12 may be of the well known type, commonly used in pneumatic despatch systems, and comprise a barrel consisting of an outer and inner shell 12^a and 12^b telescopically arranged and relatively rotatable, each shell having an access opening 12^c which may be brought into and out of register by rotation of the shells 12^a and 12^b. When the carrier is in closed position, i. e., with the access openings 12^c of the shells out of register, a cylindrical peripheral surface is provided, but when the access openings 12^c are in register, the openings provide a chordal recess in the peripheral surface of the carriers.

My invention provides means to prevent the insertion of the carriers 12 in the trays when

they are in closed position to avoid any danger that the attendant at the carrier station fails to open the carrier to remove the change or other contents. Stated another way, the rack, according to my invention, includes means to insure that the carriers must first be opened before they are filed away for use in connection with a subsequent transaction.

Accordingly, each of the trays 11 is provided with a centrally disposed inwardly projecting surface 17, herein illustrated as comprising a vertically disposed strip attached to the back panel member 13, although it is obvious that the projecting surface 17 may be formed as an integral part of the back member. It will be apparent that one side of the trays 11, as viewed in cross section (see Fig. 3) is not a plane surface and will not accommodate a wholly cylindrical body or carrier, and that said carrier must be rotated to open position so that its surface presents a chordal recess, before it may be inserted in the trays.

The upper portion of the rack 10 and trays 11 may be formed as a head member 18 providing a longitudinal channel 19, for the reception of an indicia strip 20, carrying suitable identifying indicia for the respective trays 11, as for example, "C. O. D. lay-away"; "Charge-send"; "Charge-take"; and "Cash." Conveniently the carriers may carry suitable identifying indicia as for example, colored bands, for identification with respective trays.

The back of the rack 10 may be provided with a plurality of pockets 21 for special carriers in alignment with the respective trays 11, and formed by a front strip 22 spaced from the front panel member 13, by means of partitions 23. The pockets 20 provide receptacles for the reception of certain merchandise, delivered to the wrapping station, and this constitutes a convenient receptacle for such merchandise awaiting wrapping, while still segregating such merchandise according to the character of sales.

Preferably a heading and indicia strip 23, similar to the strips 18-20 is provided in the front of the rack either at the top thereof, or some other prominent part, as for example the front strip 21.

The numerous advantages of the invention will be readily apparent to persons skilled in the art to which the invention relates.

I claim:

1. A rack for pneumatic dispatch carriers of the type comprising relatively rotatable apertured cylindrical shells presenting a substantially cylindrical body having a channel means in the surface thereof when in opened position;

said rack comprising a plurality of vertically arranged trays, each formed with an opening near the top thereof for the insertion of said carriers, means projecting within the trays for preventing insertion of the carriers therein when they are in closed position, and means permitting withdrawal of said carriers from the trays adjacent the bottom thereof.

2. A rack for pneumatic dispatch carriers of the type comprising relatively rotatable apertured cylindrical shells presenting a substantially cylindrical body having a channel means in the surface thereof when in opened position; said rack comprising a plurality of separate vertically arranged trays, each formed with an opening near the top thereof for the insertion of the carrier therein, each of said trays being of a cross-sectional configuration corresponding to the outline of said carriers when in opened position including a part extending within the chordal recess of said carriers, and means permitting the withdrawal of said carriers from said trays adjacent the bottom thereof.

3. A rack for pneumatic dispatch carriers of the type comprising relatively rotatable apertured cylindrical shells presenting a substantially cylindrical body having a channel means in the surface thereof when in opened position; said rack comprising a plurality of separate vertically arranged trays, each formed with an opening near the top thereof for the insertion of the carrier therein, each of said trays being of substantially rectangular cross-section having a centrally disposed inwardly extending projection conforming to the shape of the carrier when open, whereby insertion of the carriers in the trays when in closed position is prevented, and means permitting withdrawal of said carriers from the trays adjacent the bottom thereof.

4. A rack for pneumatic dispatch carriers of the type comprising relatively rotatable apertured cylindrical shells presenting a substantially cylindrical body having a channel means in the surface thereof when in opened position; said rack comprising a back member, a plurality of separate carrier trays formed on the front face of said back member, means for separating said trays according to a predetermined selected character of sale, means within the trays for preventing insertion of the carriers in the trays when the carriers are in closed position, and guide means spaced from said back member for confining the carriers in the trays, said guide means being spaced from the bottom of the trays providing an opening permitting removal of the carriers from the trays.

WILLIAM O. HUMPHRIES.
